UNITED STATES PATENT OFFICE

STUART PARMELEE MILLER, OF GLEN RIDGE, NEW JERSEY, ASSIGNOR TO THE BARRETT COMPANY, OF NEW YORK, N. Y., A CORPORATION OF NEW JERSEY

RECOVERY OF TAR ACIDS

Application filed July 16, 1927. Serial No. 206,370.

This invention relates to the recovery of tar-acids and ammonia, as well as other products, at coal distillation plants, such as coke oven plants.

5 According to the present invention, the hot coal distillation gases, such as coke oven gases, are subjected to cooling to cool them to a regulated temperature, above the dew point of water, at which a pitch of low melting point will be carried in suspension in the gases and at which a considerable amount of the tar-acids will remain in vapor state, then cleaned to remove a low melting point pitch therefrom, for example, with an electrical precipitator, then passed through an ammonia absorber or saturator at a temperature above the dew point of water and a temperature such that the tar acids will remain largely in the vapor state, then cooled 20 to separate a tar-acid oil therefrom, and then finally subjected to a scrubbing or absorbing treatment for the recovery of coke oven light oils. The tar-acids are extracted from the tar acid oil.

25 The present invention is an improvement in direct ammonia processes in which the ammonia is directly absorbed from the hot coke oven gases at a temperature above the dew point of water, and combines such direct ammonia recovery with the direct recovery from the gases of a low melting point pitch prior to the recovery of ammonia and of a tar-acid oil subsequent to the recovery of the ammonia, from which tar-acids can be directly extracted, thus eliminating the need of distilling tar to recover a distillate oil from which tar-acids can be extracted, and a pitch residue.

30 The production of direct ammonia and of tar acids, according to the present invention, can be advantageously combined with the direct production of pitch of regulated melting point, suitable for use directly as a commercial product, for example, for road making or treating purposes.

35 According to the present invention, the coke oven gases are cooled to a regulated temperature, e. g. around 110 to 120° C., and the gases are then subjected to a cleaning treatment for the separation of pitch there-

from. This cleaning treatment may advantageously be with an electrical precipitator, which will separate from the gases the pitch particles carried in suspension therein, leaving clean gases containing ammonia and tar 55 acid oils in vapor form.

By maintaining the gases at a temperature around 110 to 120° C., or somewhat higher, there can be directly separated from the gases in the electrical precipitator a pitch 60 of melting point adapting it for use directly for road making or treating surfaces, for example, a pitch having a melting point around 105° F. (or 40.5° C.). The removal of pitch particles from the gases at such temperatures 65 will leave the gases at a temperature considerably above the dew point of water, and the gases will still contain a considerable amount of the tar acid content of the gases in vapor form, together with oil constituents in 70 vapor form. By subjecting the cleaned gases to the action of sulphuric acid in a saturator or absorber, the gases can be freed from ammonia, and can then be advantageously cooled for the separation of a tar acid 75 oil therefrom. This cooling can be effected either indirectly or directly by the introduction of water into the gases. The cooling of the gases by direct contact with water has the advantage that since ammonia is absent 80 from the gases, the water does not require subsequent treatment for the recovery of ammonia therefrom. The cooling of the gases for the separation of the tar acid oil may be, for example, to a temperature around 25° 85 to 30° C., after which the gases can be passed to an absorber or scrubber for the recovery of coke oven light oils, including benzol, etc.

In carrying out the process of the invention, the hot coke oven gases from the individual ovens may be collected in a common collector main in the ordinary way, and subjected therein to regulated cooling with ammonia liquor, or with ammonia liquor and tar. The cooling should be regulated so that the gases leaving the collector main are at a sufficiently high temperature so that they can be passed through a cleaning device, such as an electrical precipitator, at a sufficiently high temperature to remove a pitch product 95 100

of commercial properties therefrom, while leaving a considerable amount of the tar acid oil in the vapor state. The cooling of the gases in the collector main will throw down a considerable amount of heavy tar, which may carry with it some of the tar-acids separated from the hot coke oven gases by the local over-cooling of part of the gases in contact with the ammonia liquor, but the 10 gases as a whole will be maintained at a sufficiently high temperature on leaving the collector main so that they carry in suspension pitch particles and tar acid oil vapors. By then subjecting the gases to the action of the 15 electrical precipitator, the pitch particles will be separated therefrom in the form of a pitch of the desired melting point, while the clean gases will contain the tar acid oils in vapor form and can then be passed directly to the 20 ammonia absorber or saturator, and then to a cooler for the separation of tar acid oils.

The pitch separated in the electrical precipitator may contain some water, where ammonia liquor is carried in suspension in the 25 gases entering the precipitator, or where water is condensed by local over-cooling of some of the gases. In such case the pitch can be heated in the bottom of the electrical precipitator to free it from water so that the 30 pitch drawn off from the precipitator will be suitable for use directly, or for shipment, without requiring further treatment. This pitch, therefore, forms one of the valuable 35 directly recovered products of the process, being a pitch of regulated melting point as directly recovered from the hot gases and, if desired, in a water-free condition.

It will be seen that the present invention involves the production or separation from 40 the hot coke oven gases first of a heavy tar and then of a low melting point pitch before the gases are passed through the ammonia absorber. The heavy tar will, moreover, be separated from the gases before the separation 45 therefrom of the low melting point pitch, and the heavy tar separated may be at a lower temperature than the temperature of the pitch, even though the gases from which it is separated are at a higher temperature. 50 When ammonia liquor is employed for cooling the gases in the collector main, and in the goose-neck through which the gases enter the collector main, the ammonia liquor will come into direct contact with a part of the gases, 55 and will cool such part of the gases so that a heavy tar will be separated therefrom. Part of the gases, however, will not come into contact with the ammonia liquor and will remain 60 at a high temperature, so that the mixture of gases leaving the collector main and passing to the electrical precipitator may be at a materially higher temperature than that to which part of the gases are subjected in the 65 collector main, although materially lower

than that of part of the gases passing through the collector main.

In the electrical precipitator local over-cooling is undesirable, since the action desired is the throwing out of the gases of suspended particles of low melting point pitch carried thereby, so as to leave gases free from such pitch constituents for passage to the ammonia absorber. The temperature to which the gases are cooled in the collector main, and at which they pass through the precipitator, can advantageously be regulated by noting the melting point of the pitch separated in the precipitator and raising or lowering the temperature of the gases to increase or decrease the melting point of the pitch when it is of too low or too high a melting point.

The composition of coal distillation gases varies somewhat with the particular coal or mixture of coal being coked, the temperature and rate of heating during the coking operation, etc., but where, for example, it is desired to make a low melting point pitch having a melting point around 105° to 110° F. (or 40.5° C. to 43.5° C.), the particular temperature to be maintained for the gases undergoing treatment can readily be ascertained. With certain coke oven gases this temperature was found to be around 110° to 120° C. Such temperatures are sufficiently high not only to give a low melting point pitch suitable for use directly for road treating and other purposes, but to maintain in the gases a considerable amount of tar acid oil vapors so that, after the gases have been passed through the electrical precipitator above the dew point of water, they can be subsequently cooled to separate a tar-acid oil therefrom, which can be directly extracted, for example, with a caustic soda solution to 100 separate the tar acids therefrom.

In my companion case, Serial No. 202,736 filed June 30, 1927, I disclosed a process of recovering tar acid oils directly from hot coke oven gases by cleaning the gases at a sufficiently high temperature to leave tar acid oils in the vapor state; then cooling the gases to separate the tar acid oil therefrom, and then passing the gases through the ammonia absorber. The process of the present invention is distinguished from such process, in that it involves subjecting the gases to the action of the acid bath in the saturator or absorber at a sufficient temperature to leave tar acid oils in vapor form, and then subsequently cooling to condense tar acid oils before the gases are subjected to the final scrubbing for the recovery of coal tar light oils.

The process of the present invention is also distinguished from the process of my companion application Serial No. 206,365, filed July 16, 1927 in that the present process involves the direct production of a low melting point pitch, suitable, for example, for use for road-treating purposes, while the process of 130

my companion application involves the production of a relatively high melting point pitch and of a creosote oil directly from the gases before they pass through the ammonia absorber. The process of the present invention, like that of my said companion application, involves subjecting the gases leaving the saturator to two successive recovery treatments; first for the recovery of tar acid oils, and finally for the recovery of coke oven light oils.

The extraction of the tar acids from the tar acid oil can be effected by treatment of the oil with a solution of a phenol-combining substance, such as caustic soda, as more fully described in my companion application Serial No. 202,736, using, for example, a ten per cent solution of caustic soda, although a stronger or more dilute solution can be employed. When the caustic soda in the solution has been used up in the formation of sodium salts of the tar acids or phenols, the resulting phenolate solution can be subjected to treatment with carbon dioxide, for example, to set free the phenols and to form sodium carbonate, the last of the phenols being set free by adding a small amount of sulphuric acid. The phenols thus set free can be separated from the sodium carbonate solution and further distilled or refined to produce commercial products or fractions therefrom.

In some cases the tar acid oil may also be rich in naphthalene. In order to prevent separation of naphthalene, the extraction of the tar acids should be carried out at a temperature sufficiently high to keep the naphthalene in a liquid state. After the extraction of the tar acids from the oils, the naphthalene content will be considerably increased, and, by cooling the neutral oils, naphthalene may be directly separated therefrom in crystalline form, thus enabling naphthalene, as well as tar acids, to be directly recovered at the coke oven plant.

The invention will be further described in connection with the accompanying drawings, which are somewhat diagrammatic and conventional in character, and which illustrate an apparatus embodying the invention and adapted for the practice of the process of the invention.

In the drawings, Fig. 1 is a plan view showing in a more or less diagrammatic manner apparatus for carrying out this invention;

Fig. 2 is a cross section through the collector main and electrical precipitator of Fig. 1;

Fig. 3 is a cross sectional elevation of the precipitator shown in Fig. 2; and

Fig. 4 is a diagrammatic view of suitable extraction apparatus.

Referring to the drawings, 5 indicates a battery of coke ovens in which the individual ovens are connected by uptake pipes and 65 goose-necks 6 to a collector main 7 having

center-box 8. Ammonia liquor and tar can be supplied to the collector main and goose-necks in regulated quantity through the spray nozzles 9 and 10 from a suitable source 11 by pump 12 through the pipe 13. The amount of ammonia liquor and tar thus supplied for cooling purposes is regulated so that the gases leaving the collector main through the pipe 14 pass thru the electrical precipitator 15 at a temperature such that a pitch of commercial 75 value will be separated from the gases, and such that the gases after leaving the precipitator will pass through the saturator 17 at a temperature above the dew-point of water. The gases may pass through the precipitator 80 at a temperature of 110 to 120° C. for example. The tar and ammonia liquor which collect in the center-box of the collector main can be withdrawn through the pipe 18 into a decanter 19 from which ammonia liquor will 85 be withdrawn into the receiver 20 and tar will be collected in the tank 21.

The electrical precipitator used may be of any suitable type. It is arranged preferably closely adjacent to the collector main. The 90 electrical precipitator illustrated is designed especially for use with gases of high temperature. It consists of a shell 22 enclosing a number of tubes 23 supported in heads 24 and 25 within the shell. An inlet 26 near the bottom of the shell communicates with the chamber 27 which is partially separated from the tube section by a baffle 28. An outlet 29 permits the escape of gases from the separator.

A plurality of electrodes 30, preferably in the form of metal rods, extend through the tubes and are supported from a bus-bar 31 located near the upper ends of the tubes. The bus-bar 31 extends at both ends into casings 32 which enclose insulators 33 upon which the bus-bar is supported. The high tension current lines extend into the casings 32 and connect with the bus-bar 31, thus supplying the necessary current from any 105 suitable source of unidirectional current under high tension. The casing of the separator is grounded or otherwise connected to the source of current to complete the circuit. The casing and tubes form the positive electrode, the electrodes connected to the bus-bar 110 being negative.

The gases carrying heavy tar or pitch in the form of globules or "fog", together with solid particles such as carbon, etc., enter the electrical precipitator and pass through the tubes, being subjected therein to the electrical discharge which causes them to separate from the gases and vapors. The separated liquids, together with the solid particles, run down the inner walls of the tubes into the chamber 27 and can be withdrawn through a pipe 34 from the bottom of the precipitator. The gases carrying the condensable vapors escape through a cross-over 125 130

main 16 and are delivered thereby to the saturator 17.

The saturator illustrated is of the conventional type with a centrifuge 35 and an acid separator 36 to remove entrained acid from the escaping gases.

From the saturator the gases pass to a condenser 37 which may be of any suitable type such as the usual "wet" condenser, where the 10 gases are sprayed with water for cooling and removal of the light oil, i. e. the tar acid oil or carbolic oil. After leaving the condenser, the gases may be passed through the exhauster 38 to the cooler 37' and thence to 15 scrubber 39 to recover coke oven light oils and from there to suitable storage.

In the drawings, the condenser is illustrated as an ordinary wet condenser in which the 20 gases are sprayed with water through the pipe 40. The condensate from the condenser is drawn off into the decanter 41 from which the condensed oil is collected in the receiver 42.

To remove the tar acids from this oil, it is 25 passed through the pipe 43 to extraction apparatus 44 which may comprise a tank having suitable agitating means 45 therein. The extraction agent, for example, a 10% solution of caustic soda, can be added in suitable proportions to the tank through an inlet 46 and mingled with the oil by agitation until the extraction is accomplished. The oil can then be decanted through pipe 47 and the carbolate solution can be withdrawn 35 through an outlet 48 and subjected to any suitable treatment for the separation of the tar acids, such as treatment with carbon dioxide, and the tar acids can then be refined to produce refined or fractionated products.

40 The extraction of the tar acid oil with e. g. a caustic soda solution should be carried out at a temperature above that at which the naphthalene crystallizes out, unless any excess of naphthalene is first removed from 45 the oil by cooling to a low temperature. After the separation of tar acids, the oil if rich in naphthalene can be cooled to crystallize naphthalene therefrom in a relatively pure state. Naphthalene, as well as tar acids 50 can thus be directly recovered as a commercial product of the process.

It will thus be seen that the improved process of the invention provides not only for the direct recovery of ammonia from the coke oven gases at a temperature above the dew-point of water, so as to avoid condensation of water during the ammonia absorption, but also for the recovery of a commercial 60 pitch product from the gases prior to the ammonia recovery, and the recovery of both a tar acid oil from which tar acids are extracted and also of coke oven light oil after the gases have been freed from ammonia, so that 65 except for the heavy tar separated in the col-

lector main, the products of the process are directly recovered commercial products.

I claim:

1. The method of treating hot coal distillation gases, which comprises cooling the 70 gases to a regulated temperature such that when cleaned with an electrical precipitator, there will be directly separated therefrom a pitch having a melting point of about 105° to 110° F., and a considerable amount of tar 75 acid oils will be left in the vapor state, cleaning the gases by electrical precipitation subsequently treating the resulting cleaned gases for the recovery of ammonia at a sufficiently high temperature to leave tar acids 80 in vapor form, treating the resulting gases for the recovery of tar acid oils therefrom, and extracting tar acids from such oils.

2. The method of treating coke oven gases which comprises cooling the same to a regulated temperature 110 to 120° C., passing 85 the gases at such temperature through an electrical precipitator to separate therefrom a pitch product suitable for use for road treating purposes, subjecting the resulting 90 cleaned gases to treatment with sulphuric acid for the recovery of ammonia therefrom at a temperature above the dew point of water, cooling the gases to separate tar acid oils therefrom and extracting tar acids from 95 such oils.

3. The method of recovering tar acids, which comprises removing from hot coal distillation gases heavier tar constituents and ammonia at a temperature sufficiently 100 high to leave a considerable amount of tar acid oils in the vapor state, cooling the resulting cleaned gases to separate tar acid oils therefrom, and extracting tar acids from such oils.

4. The method of recovering tar acids and naphthalene from hot coke oven gases, which comprises removing heavier tar constituents and ammonia from such gases at a temperature sufficiently high to leave a considerable 110 amount of tar acid oils and naphthalene in the vapor state, cooling the resulting cleaned gases to separate tar acid oils containing naphthalene therefrom, extracting such oils to separate tar acids therefrom at a temperature above that of separation of the naphthalene, and subsequently cooling the oils to separate naphthalene therefrom.

5. The method of treating hot coal distillation gases which comprises cooling the 120° gases to a regulated temperature, 110 to 120° C. such that they carry in suspension pitch particles of a melting point adapting them for use for road treating purposes, subjecting the gases at such regulated temperature 125 to an electrical discharge thereby effecting the separation of such pitch particles therefrom, and thereby obtaining directly from the gases a pitch suitable for road treating purposes.

6. The method of treating hot coal distillation gases which comprises cooling the gases to such a temperature that suspended particles of pitch condensate with a melting point of 105° to 110° F. (40.5° to 43.5° C.)

5 10 15

form therein, subjecting the resulting mixture of gases and entrained pitch particles to cleaning by effecting an electrical discharge therein whereby a pitch product having a melting point of 105° to 110° F. is separated from the gases.

7. The method of treating hot coal distillation gases which comprises cooling the gases to 110-120° C., cleaning the gases by subjecting them to an electrical discharge 15 to remove therefrom a pitch suitable for road treating purposes, and subsequently cooling the resulting gases to separate therefrom an oil containing tar acids.

20 In testimony whereof I affix my signature.
